Inventor

Simon T. Peek

UNITED STATES PATENT OFFICE.

SIMEON T. PEEK, OF PENFIELD, GEORGIA.

IMPROVEMENT IN PLOWS.

Specification forming part of Letters Patent No. **26,289**, dated November 29, 1859.

To all whom it may concern:

Be it known that I, SIMEON T. PEEK, of Penfield, in the county of Greene and State of Georgia, have invented a new and Improved Plow; and I do hereby declare that the following is a full, clear, and exact description of the same, reference being had to the annexed drawings, making a part of this specification, in which—

Figure 1 is a side view of my invention. Fig. 2 is a horizontal section of the same, taken in the line *x x*, Fig. 1. Fig. 3 is a detached perspective view of the lower part of the foot of the same. Fig. 4 is a detached perspective view of the share.

Similar letters of reference indicate corresponding parts in the several figures.

This invention relates to an improvement in that class of plows which have a shovel-shaped share attached to a foot-bar, and are generally known as "shovel-plows."

The invention consists in a novel way of attaching the share to the foot-bar, substantially as hereinafter shown, whereby an extremely simple and efficient connection is obtained, bolts and rods being avoided, and the share very readily attached to and detached from the foot-bar.

To enable those skilled in the art to fully understand and construct my invention, I will proceed to describe it.

A represents the beam of the plow, B the handles, and C a support or brace to the same. These parts are of usual construction, and therefore do not require a minute description.

D is the foot-bar, constructed of metal, and of curved form, as shown clearly in Fig. 1. This foot-bar may be attached to the beam in any proper way. The body or main portion of the foot-bar is of usual construction, but its lower part is different, as shown more particularly in Fig. 3. It will be seen by referring to this figure that a recess or rabbet, *a*, is formed at the lower end of the foot-bar, and a shoulder, *b*, produced thereby. At the upper

end of this shoulder, and at each side, there is a lateral projection, *c*, and on the upper surface of the rabbet there is a pin or teat, *d*.

E is share, which may be of the form shown in Fig. 4, or other suitable shape. The upper or back end of this share is notched or recessed, as shown at *e* in Fig. 4, said notch or recess being sufficiently wide to receive the shoulder *b*, the back ends, *f*, of the share at each side of the recess fitting underneath the projections *c c*. In the share a hole, *g*, is made to receive the pin or teat *d*.

At the face side of the foot-bar D there is a projection, *h*, through which the fulcrum-pin *h'* of a lever, F, passes. This lever F is curved, corresponding to the curvature of the foot-bar D, and between the upper end of lever F and the foot-bar a curved wedge, G, is interposed, which wedge presses the lower end of the lever firmly on the upper part of the share, and, in connection with the projections *c c*, prevents the same from moving upward from its seat, the pin or teat *d*, and the fitting of the shoulder *b* in the recess preventing any lateral movement of the share.

By this arrangement a very simple and efficient connection is obtained, all rods and bolts avoided, and one that will admit of a very ready adjustment of the share to the foot-bar.

Having thus described my invention, what I claim as new, and desire to secure by Letters Patent, is—

The manner of attaching the share E to the foot-bar D—to wit, having the back part of the share notched and fitted in a rabbet, *a*, in the foot-bar, and receiving the shoulder *b*, formed by the rabbet, while the ends *f* of the share fit underneath the projections *c c*, and the lever F is pressed on the outer side of the share by means of the wedge G—substantially as shown.

S. T. PEEK.
